UNITED STATES PATENT OFFICE.

GOTTHILF BISCHOFF, OF FREUDENSTADT, GERMANY, ASSIGNOR TO FIRM OF ERNST
GIDEON BEK, G. M. B. H., OF PFORZHEIM, GERMANY.

MANUFACTURE OF CHAIN-SWIVELS.

1,073,841.

Specification of Letters Patent. Patented Sept. 23, 1913.

Original application filed February 24, 1913, Serial No. 750,355. Divided and this application filed May 8, 1913. Serial No. 766,270.

To all whom it may concern:

Be it known that I, GOTTHILF BISCHOFF, a subject of the German Emperor, residing at Freudenstadt, Germany, have invented 5 certain new and useful Improvements in the Manufacture of Chain-Swivels, of which the following is a specification.

This application is divisional of my co-pending application, Serial No. 750,355, 10 filed February 24, 1913.

The present invention has reference to improvements in the manufacture of chain swivels, also called snap or carbine hooks, and it relates more particularly to the 15 manufacture of swivels of this character to be used mainly in connection with watch chains, and the object of the invention is to simplify and cheapen the manufacture of such swivels by assembling the specially 20 shaped and worked parts without soldering, pinning or riveting, simply by pressing or swaging.

In order to make the invention more readily understood, I will describe it now with 25 reference to the accompanying drawings, in which—

Figures 1-7 show side and front elevations, plan views and cross-sections respectively of the swivel parts in various stages 30 of manufacture; Fig. 8 represents a side elevation of a swivel hook made up of these parts, the socket or neck being shown in section.

According to this invention there is first 35 stamped out a blank, comprising a shank *a* with a plate *n*, having a slot *p*, at the one end, and a reduction *c*, oppositely disposed lugs *o* and a tongue *d* at the other end, as shown in Figs. 1, 1^a and 2. This blank is 40 then worked in suitable manner so that it assumes the formation shown in Figs. 3, 3^a, 4, with the trunnions *o* extending from either face of the plate *c*, and the tongue *d* slightly curved. The upper plate *n* is 45 rounded, and a shoulder *q* and a cross-groove *r* are presented (Fig. 4). The plate *n* is turned over rectangularly (Figs. 5 and 5^a) and the yoke or horseshoe is formed, as shown in Fig. 6, by bending the shank *a*, the 50 plate *c* entering the slot *p* and the trunnions

o taking into the respective groove-halves *r*. To the thus formed carbine proper (Fig. 7^a) is now attached the neck or socket *k* (Fig. 7^b) by the cup-shaped end of the latter being closed over the plate *n* in contact with 55 the shoulder *q*, a spring *m* co-operating with the depending tongue *d*, as shown in Fig. 8; and lastly, the swivel ring or eye *i* is secured to the socket by compressing the latter about the ball-trunnion *l*, *h*. If not previously 60 done, the yoke *a* is now slantingly severed, as at *a'* (Fig. 8), which leaves the member *g* pivoted on the trunnions *o*.

What I claim is:—

1. The method of making chain swivels, 65 which comprises stamping and pressing a blank in the form of a shank with a slotted and cross-grooved plate at the one end and with a plate having laterally projecting trunnions and a depending tongue at the other 70 end, bending the said slotted plate angularly to said shank, and then bending the latter into horseshoe-shape until the said second plate takes into the slot of the said first plate and the trunnions engage in the 75 cross-grooves thereof.

2. The method of making chain swivels, 80 which comprises stamping and pressing a blank in the form of a shank with a slotted and cross-grooved plate at the one end and with a plate having laterally projecting trunnions and a depending tongue at the other end, bending the said slotted plate angularly to said shank, then bending the latter into horseshoe-shape until the said second plate takes into the slot of said first plate and the trunnions engage in the cross-grooves thereof, then cutting the horseshoe, 85 introducing a spring into the swivel socket, and finally, attaching the latter to the carbine proper and the swivel eye by swaging or pressing, said spring being placed in co-operation with said depending swivel tongue. 90

In testimony whereof I affix my signature 95 in presence of two witnesses.

GOTTHILF BISCHOFF.
